UNITED STATES PATENT OFFICE.

AUGUSTE BRUNETTE, OF MONTREAL, QUEBEC, CANADA.

BURNER FOR PETROLEUM AND OTHER HYDROCARBONS.

1,073,326.

Specification of Letters Patent. Patented Sept. 16, 1913.

Application filed February 7, 1913. Serial No. 746,957.

To all whom it may concern:

Be it known that I, AUGUSTE BRUNETTE, a subject of the King of Great Britain, residing at Montreal, in the Province of Quebec, Canada, have invented certain new and useful Improvements in or Relating to Burners for Petroleum and other Hydrocarbons; and I do hereby declare that the following is a full, clear, and exact description of the invention, such as will enable others skilled in the art to which it appertains to make and use the same.

The invention to be hereinafter described relates to burners for petroleum or other hydrocarbons.

In order to more clearly disclose the construction, operation, and use of the invention, reference should be had to the accompanying drawings forming part of the present application.

Throughout the several figures of the drawings like reference characters designate the same parts.

In the drawings: Figure 1 is a side elevation of the invention; Fig. 2 is a top plan view; and Fig. 3 is a central, vertical, longitudinal, cross section.

The main objects of the invention are to provide a simple, efficient, durable, economical, and compact hydrocarbon burner in which the vaporized fuel will be continually maintained at an increasingly high temperature from the time that it enters the feed pipe until it is ignited in the burner.

Such an arrangement not only gives a reduced cost of production for the burner, but a maximum efficiency, resulting in a very great reduction in the quantity of fuel used for any given purpose.

Referring to the drawings in detail, the whole device, complete, is made as a single casting. The main part of this casting is a centrally arranged frusto-conical combustion tube or burner body 1, the base of

which is partly closed by an inwardly extending annular plate 3 from the center opening of which extends a short gas receiving inlet tube 4. The wall of the tube 1 is provided with a plurality of perforations 5 for inlet of air.

Extending longitudinally along one side of the tube 1 is a feed pipe 6 provided with a suitable opening 7 to give access for cleaning out. Diametrically opposite the feed pipe 6 is arranged the upper section of the jet tube 8, also provided with a suitable

opening 9 to permit access for cleaning out. The upper end of the feed tube 6 is connected to the upper section of the jet tube 8 by means of downwardly directed oblique conduits 10 formed integrally with the outer wall of the conical tube 1 and extending about opposite sides thereof. Any suitable coupling 11 may be used to couple the lower end of the feed tube on to a regular supply pipe, tank, or the like. The lower section 12 of the jet tube may be connected to the upper section by screw threads, as shown in the drawings, or any other suitable manner. When assembled, the jet tip or nozzle 13 falls directly beneath the open end of the gas receiving inlet tube 4.

In operation, the hydrocarbon will be supplied to the feed pipe 6 in any usual manner; the feed pipe, being an integral part of the conical tube 1 and extending lengthwise thereof, will be highly heated by the flame within the conical tube; this heated fuel will then pass obliquely downward through the conduits 10 which also form an integral part of the conical tube and extend thereabout, being also highly heated thereby; and from the lower ends of these conduits the fuel will pass into the upper section 8 of the jet tube which is also integral with, extends lengthwise of, and is highly heated by, the conical tube 1. This very highly heated hydrocarbon finally reaches the jet tip 13 from which it issues as a fine jet or spray of vaporized hydrocarbon. Passing up through the inlet tube 4 and into the interior of the conical combustion tube 1, it mixes with air flowing in through the small air inlet perforations 5 and becomes ignited, the ignited mixture giving an intense heat. The upwardly directed flame and heated gases act to create a suction through the air perforations, thus keeping up the continual feed of air necessary for the mixture.

It is thought that the construction, operation, and use of the invention will be clear from the preceding detailed description.

Having thus fully described my invention, what I claim as new and desire to secure by Letters Patent is:

1. A device of the character described comprising, a combustion tube, a feed pipe extending longitudinally along one side of the outer wall thereof, a burner tube section extending longitudinally along the op-

posite side of the outer wall thereof, and conduits extending diagonally downwardly about the outer wall of said combustion tube and communicating at their opposite ends with said feed tube and said burner tube respectively.

2. A device of the character described comprising a single casting consisting of, a combustion tube, a feed pipe extending longitudinally along one side of the outer wall thereof, a burner tube section extending longitudinally along the opposite side of the outer wall thereof, and conduits extending

diagonally downwardly about the outer wall of said combustion tube and communicating at their opposite ends with said feed tube and said burner tube respectively. 15

In witness whereof I have hereunto set my hand in the presence of two witnesses.

Signed at Montreal this twenty third day 20 of January, 1913.

AUGUSTE BRUNETTE.
